O. WOOTEN.
WAGON BRAKE ROD CONNECTION.
APPLICATION FILED SEPT. 10, 1908.

911,355.

Patented Feb. 2, 1909.

UNITED STATES PATENT OFFICE.

OWEN WOOTEN, OF PACIFIC, MISSOURI.

WAGON-BRAKE-ROD CONNECTION.

No. 911,355.

Specification of Letters Patent.

Patented Feb. 2, 1909.

Application filed September 10, 1908. Serial No. 452,406.

To all whom it may concern:
Be it known that I, OWEN WOOTEN, a citizen of the United States, and resident of Pacific, Franklin county, Missouri, have invented certain new and useful Improvements in Wagon-Brake-Rod Connections, of which the following is a specification, containing a full, clear, and exact description, reference being had to the accompanying drawings, forming a part hereof.

My invention relates generally to wagon brakes, and more particularly to an improved connecting member between the brake rod or cable and the rock shaft which is arranged adjacent the rear axle of the wagon, and which rock shaft is connected to the brake beam, the object of my invention being to construct a simple, inexpensive connecting member which may be readily attached to the brake rod or to the cable which extends to the winding shaft at the forward end of the wagon bed, and which connecting member is provided with a pair of spring jaws, one of which carries a series of pins which are adapted to engage through an aperture in the crank carried by the end of the rock shaft.

A further object of my invention is to construct the connecting member with a pair of spring jaws and to provide a combined key and lock for said jaws, which key is adapted to be partially rotated to open the jaws and to hold said spring jaws together when the connecting member is engaged on the crank of the rock shaft.

To the above purposes, my invention consists in certain novel features of construction and arrangement of parts, which will be hereinafter more fully set forth, pointed out in the claims, and illustrated in the accompanying drawings, in which:—

Figure 1 is a perspective view of a connecting member of my improved construction, with the combined key and lock removed; Fig. 2 is a plan view of a portion of a wagon frame, and showing my improved connecting member arranged between the crank on the end of the rock shaft and the cable which extends forward to the brake setting mechanism; Fig. 3 is a plan view, partly in section, showing the connecting member sprung open by means of the combined key and lock; Fig. 4 is an enlarged cross section taken on the line 4—4 of Fig. 2; Fig. 5 is an enlarged cross section taken on the line 5—5 of Fig. 3.

The body of my improved connecting member comprises a pair of jaws 1 and 2 in

the form of elongated parallel plates, the rear ends of which are joined by a loop 3; and which loop acts as a spring to force the jaws 1 and 2 toward one another. This loop 60 3 also provides means for attaching the rear end of the cable 4 which leads from the forward end of the wagon frame to the brake setting mechanism; and formed integral with this loop 3 is a shank 5, which may be rigidly 65 attached by welding to the brake rod, which arrangement is carried out where the cable 4 is not used. The free ends of the jaws 1 and 2 are spaced apart, and rigidly fixed in one jaw is a series of horizontally disposed pins 6, 70 the free ends of which enters apertures 7 formed in the opposite jaw.

Formed on the inner faces of the jaws 1 and 2, between the loop 3 and the series of pins 6, are the pairs of vertically disposed 75 ribs 8, the faces of which engage against one another when the jaws are closed, thus forming a slot 9; and positioned in this slot is a plate 10, which forms the body of the combined key and lock, there being a head 11 80 formed integral with the top of said plate, and a lug 12 with the lower end thereof. Formed integral with the plate 11 is a pair of depending fingers 12, which are adapted 85 to engage against the jaws 1 and 2 to prevent the same from spreading when the device is in use.

A designates the rock shaft which is connected to the brake beam B; and formed integral with one end of said rock shaft is a 90 crank C, which is provided with an aperture, (not shown), adapted to receive one of the pins 6.

When my improved connecting member is in use, it is attached to the cable 4, as shown in Fig. 2, or is rigidly connected to the end of a brake rod; and when it is desired to engage the crank C, the head 11 of the combined key and lock is engaged and the plate 10 is elevated until the lower ends 95 of the fingers 12 are drawn above the upper edges of the jaws, after which the plate 10 is rotated approximately one-quarter of a turn; or until it occupies a position at right angles to the jaws 1 and 2, which action 105 springs the free ends of the jaws apart, (as shown in Fig. 3,) thus drawing the free ends of the pins 6 out of the apertures 7. One of the pins 6 is now engaged through the aperture in the crank arm C, after which the key 110 is rotated to its original position, which permits the jaws to spring together, and the

key is now allowed to drop so that the fingers 12 engage on opposite sides of the jaws 1 and 2, thus preventing the same from spreading, which action would release the crank arm C.

5 By providing a plurality of the pins 6, adjustment between the brake rod and rock shaft A is provided, thus compensating for any slack which may occur in the brake mechanism, or for any wear of the brake 10 shoes.

A connecting member of my improved construction is simple, inexpensive, easily applied for use, and is adapted for all forms of wagon brakes.

15 I claim:—

1. A connecting member for wagon brakes, comprising a pair of spring jaws rigidly connected to one another at one end and there being a loop formed at the connected ends, a 20 series of pins carried by one jaw and engaging in apertures formed in the opposite jaw, and a key carried by said member for spreading the jaws.

2. A connecting member for wagon brakes, 25 comprising a pair of spring jaws, a series of pins carried by one jaw and engaging in

apertures formed in the opposite jaw, a key carried by said member for spreading the jaws, and means carried by said key for normally holding the jaws against spreading. 30

3. A connecting member for wagon brakes, comprising a pair of parallel jaws, a loop connecting the jaws at one end, a series of pins seated in one jaw and entering corresponding apertures formed in the opposite jaw, and 35 a combined key and lock held between said jaws.

4. A connecting member for wagon brakes, comprising a pair of parallel jaws, a loop connecting the jaws at one end, a shank 40 formed integral with said loop, a series of pins seated in one jaw and entering corresponding apertures formed in the opposite jaw, and a combined key and lock held between said jaws.

In testimony whereof, I have signed my name to this specification, in presence of two subscribing witnesses.

OWEN WOOTEN.
